W. WALDSCHMITT.

TRAVELING BAG.

APPLICATION FILED FEB. 16, 1912.

1,145,949.

Patented July 13, 1915.

UNITED STATES PATENT OFFICE.

WILLIAM WALDSCHMITT, OF BROOKLYN, NEW YORK.

TRAVELING-BAG.

1,145,949.

Specification of Letters Patent. Patented July 13, 1915.

Application filed February 16, 1912. Serial No. 677,986.

To all whom it may concern:

Be it known that I, WILLIAM WALDSCHMITT, a citizen of the United States, and a resident of Brooklyn, in the county of 5 Kings and State of New York, have invented certain new and useful Improvements in Traveling-Bags, of which the following is a specification.

The invention relates to improvements in 10 traveling bags, and it consists in the novel features and structure hereinafter described, and particularly pointed out in the claims.

The object of the invention is to provide 15 an improved traveling bag and at the same time to reduce the labor and expense of manufacturing traveling bags of the class to which my invention pertains, the bag of my invention being capable of being manufactured at considerably less labor and expense 20 than bags of the same general class have heretofore required, and also being of increased durability and desirability.

It has heretofore been customary if not 25 universal in the manufacture of bags of the general character to which my invention pertains, to provide a leather or other lining which has had its parts separately sewed together and an exterior leather casing having its parts separately sewed together, 30 whereas in accordance with my invention I secure together by pasting the outer parts for the sides and ends of the bag, a filler and a lining, and fasten all of these parts together by single lines of sewing at the corners of the bag, thereby dispensing with the 35 work of sewing the parts of the lining separately and also with the operators who have heretofore been accustomed to do that work. The bottom of my bag will preferably comprise 40 an outer rectangular piece of vulcanized fiber, a filler and a lining, all pasted together, and the lower edge portions of the sides and ends of the bag will be folded under said bottom and secured thereto by 45 riveting. At each of the four lower corners of the bag I provide a protecting corner-piece extending against the side, end and bottom of the bag and riveted thereto.

The invention will be fully understood 50 from the detailed description hereinafter presented, reference being had to the accompanying drawings, in which:

Figure 1 is a side elevation of a traveling bag constructed in accordance with and embodying my invention; Fig. 2 is a vertical

transverse section of the same on the dotted line 2—2 of Fig. 1 and showing the bag on a larger scale; Fig. 3 is a central vertical longitudinal section through an end portion of the bag on the dotted line 3—3 of Fig. 2; Fig. 4 is an end view of the bag shown on a reduced scale and as having been fully opened; Fig. 5 is a vertical longitudinal section of a portion of the same, on a larger scale, on the dotted line 5—5 of Fig. 4, and Fig. 6 is a horizontal section through a portion of one corner of the bag, taken on the dotted line 6—6 of Fig. 2.

In the drawings 10 designates the sides of the bag, 11 the ends thereof, 12 the bottom 70 of the bag, 13 the usual hinged frames to which the sides and ends of the bag are at their upper edges secured, and 14 the customary handle fastened to the outer inclosing one of said frames 13.

The sides 10 of the bag comprise an outer leather-layer 15, an inner lining-layer 16 preferably of leather, and a filler-layer 17 preferably of vulcanized fiber or equivalent material, and these three layers are securely 80 pasted or glued together to form what is in effect a single thickness of material, which is thereafter suitably cut or trimmed to the requisite shape or proportions for the sides of the bag. The outer leather layer 15 may 85 be in one integral piece but it is more economical in cutting the leather to form said layer in two horizontal sections sewed together along their adjacent edges, as at 18.

The ends 11 of the bag comprise an outer leather-layer 19, an inner lining-layer 20 preferably of leather, and an intermediate or filler-layer 21 preferably of vulcanized fiber or equivalent material, and these three layers are securely pasted or glued together 90 to form what is in effect a single thickness of material, which is thereafter suitably cut or trimmed to the requisite shape or proportions for the ends of the bag. The outer leather-layer 19 may be in one integral piece 95 but it is more economical in cutting the leather to form said layer in two horizontal sections sewed together along their adjacent edges, as at 22. The upper portions of the

filler-layers 21 are cut out, as indicated by the dotted line 23 in Fig. 4, so that the thickness of the ends of the bag within the outline of said recesses will comprise only the layers 19, 20, as shown in Fig. 4, and so that thereby the upper portions of the ends of 110

the bag may, on the closing of the hinged frames 13, fold inwardly in the manner represented in Figs. 1, 2 and 3.

The bottom 12 of the bag comprises a lower layer 24 of strong vulcanized fiber, an upper layer 25 of leather and an intermediate layer 26 of vulcanized fiber, and these three layers are finally, though not initially, pasted or glued together. The strong lower layer 24 is secured along its edges by rivets, tacks or nails 27, to the lower inwardly extended edges 28 of the sides and ends of the bag, and thereafter the layers 25, 26 pasted or glued together are glued upon the upper surface of the aforesaid layer 24 and cover the inner ends of said nails 27.

I provide protecting corner pieces 29 at the four lower corners of the bag, said pieces being secured by nails 30 and made from durable material, such as strong leather. The horizontal nails 30 extend through all the layers of the sides and ends of the bag and at their inner ends become exposed within the bag, as shown in Figs. 2 and 3, and these exposed ends will in the finishing of the bag preferably be concealed by pasting small leather disks over them. The vertical nails 30 extend through the bottom layer 24 and their inner upper ends are concealed by the layers 25, 26 positioned thereover.

In the manufacture of the bag the vertical corner edges thereof are secured, by single lines of sewing 31, and each of these lines of sewing is exterior to the bag and extends through the three layers of the side and three layers of the end of the bag, the sides and ends of the bag at their adjacent edges being faced outwardly against each other and then sewed together. The pasting together of the layers of the sides and ends of the bag enable me to complete the vertical corners of the bag by the single exterior lines of sewing 31, and to dispense entirely with the separate sewing together of the parts composing the usual lining and with the operatives who ordinarily do that work, and in addition the bag as I construct it is more durable than bags as heretofore made and better adapted to resist the severe usage to which traveling bags are frequently subjected.

What I claim as my invention and desire to secure by Letters Patent, is:

1. A traveling bag having a bottom, hinged frames at its top and a handle, the sides and ends of said bag each comprising an outer leather layer, a lining layer and a stiffening intermediate layer all pasted together to constitute in effect a single sheet and at their adjoining vertical edges being

faced outwardly against each other, as shown, and sewed together, whereby the exterior leather, filler and lining are secured at each corner of the bag by an exterior line of sewing, said intermediate layer being cut out at its upper portion; substantially as set forth.

2. A traveling bag having a bottom, hinged-frames at its top and a handle, the sides and ends of said bag each comprising an outer leather layer, an inner leather lining layer and an intermediate vulcanized fiber layer all pasted together to form in effect a single sheet and said sides and ends at their adjoining vertical edges being faced outwardly against each other, as shown, and sewed together, whereby the exterior leather, filler and lining are secured at each corner of the bag by an exterior line of sewing, said intermediate layer being cut out at its upper portion; substantially as set forth.

3. A traveling bag having a bottom comprising a strong piece of vulcanized fiber, a layer of vulcanized fiber thereon and a lining layer, all pasted together, and the sides and ends of said bag each comprising an outer leather layer, an inner lining layer and an intermediate vulcanized fiber layer all pasted together to form in effect a single sheet, and said sides and ends at their lower edges being turned under and secured to said bottom and at their adjoining vertical edges being faced outwardly against each other, as shown, and sewed together, whereby the exterior leather, filler and lining are secured at each corner of the bag by an exterior line of sewing, said intermediate layer being cut out at its upper portion; substantially as set forth.

4. A traveling bag having sides and ends each comprising an outer leather layer, a leather lining layer and an intermediate layer of stiffening material all pasted together to form in effect a single sheet, and said sides and ends at their adjoining vertical edges being substantially correspondingly faced outwardly on angular lines against each other and sewed together by exterior lines of sewing, the upper middle portions of the intermediate layers of said ends being cut out; substantially as set forth.

Signed at New York city, in the county of New York, and State of New York, this 15th day of February A. D. 1912.

WILLIAM WALDSCHMITT.
